NOTE-INDICATING PIANO FOR EDUCATION
AND AMUSEMENT

Dorothy B. Billingslea, Evanston, Ill.

Application December 29, 1954, Serial No. 33,725

Term of patent 3½ years

(Cl. D25—1)

FIG. 1

FIG. 2

Fig. 1 is a perspective view of a note-indicating piano for education and amusement, showing my new design, with the natural keys in normal position and the note-indicating slides concealed; and

Fig. 2 is a fragmentary perspective view thereof with the natural keys depressed and the note-indicating slides visible.

The legible matter shown in broken lines is for illustrative purposes only.

I claim:

The ornamental design for a note-indicating piano for education and amusement, as shown and described.
